Primary Examiner—Sandra L. Morris*Attorney, Agent, or Firm*—Harpman & Harpman[57] **CLAIM**

The ornamental design for a combined remote control cover and protector, as shown and described.

DESCRIPTION

FIG. 1 is a front, top and side perspective view of the combined remote control cover and protector embodying the design of the present invention;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.

1 Claim, 3 Drawing SheetsFIG.1.

FIG. 2.

FIG. 4.

FIG. 6.

FIG. 3.

FIG. 5.
